US00D612857S

(12) **United States Design Patent**
Bashan et al.

(10) **Patent No.:** US D612,857 S
(45) **Date of Patent:** ** Mar. 30, 2010

(54) **ELECTRONIC CARD**

- (75) Inventors: **Oded Bashan**, Rosh Pina (IL); **Ronnie Gilboa**, Upper Galilee (IL)
- (73) Assignee: **Easy Park Ltd.**, Rosh Pina (IL)
- (**) Term: **14 Years**
- (21) Appl. No.: **29/347,003**
- (22) Filed: **Aug. 24, 2009**

Related U.S. Application Data

- (63) Continuation of application No. 29/287,768, filed on Sep. 17, 2007.
